US00D968646S

(12) **United States Design Patent** (10) **Patent No.:** **US D968,646 S**
(45) **Date of Patent:** **** Nov. 1, 2022**

(54) **BUILDING**

- (71) Applicant: **MSG Entertainment Group, LLC**,
New York, NY (US)
- (72) Inventors: **James Lawrence Dolan**, Oyster Bay,
NY (US); **David Ernest Dibble**, San
Francisco, CA (US); **Jonathan
Lawrence Mallie**, New York, NY (US);
Aric Gabriel Braselton, Kansas City,
MO (US); **Nicholas Craig Reynolds**,
London (GB); **Maria Charlotta
Knutsson-Hall**, London (GB); **Cawsie
Jijina**, Boca Raton, FL (US)
- (73) Assignee: **MSG Entertainment Group, LLC**,
New York, NY (US)

(**) Term: **15 Years**

(21) Appl. No.: **29/800,510**

(22) Filed: **Jul. 21, 2021**

(51) LOC (13) Cl. **25-03**

(52) U.S. Cl.

USPC **D25/13; D25/19**

(58) **Field of Classification Search**

USPC D25/1, 7, 13, 18, 19, 31, 33

Primary Examiner — Leanne Was-Englehart

(74) Attorney, Agent, or Firm — Sterne, Kessler,
Goldstein & Fox P.L.L.C.

(57) **CLAIM**

The ornamental design for a building, as shown and
described.

DESCRIPTION

FIG. 1 is a top perspective view of a building showing the
claimed design;

FIG. 2 is a rear view thereof;

FIG. 3 is a front view thereof;

FIG. 4 is a right side view thereof;

FIG. 5 is a left side view thereof; and,

FIG. 6 is a top view thereof.

The broken lines in the figures show portions of the building
that form no part of the claimed design.

The dot-dash broken lines in the figures show boundaries
that form no part of the claimed design.

1 Claim, 6 Drawing Sheets
